STANLEY G. MILLER, OF ST. PAUL, MINNESOTA, ASSIGNOR TO CREX CARPET COMPANY,
OF ST. PAUL, MINNESOTA, A CORPORATION OF DELAWARE.

GRASS CARPET.

1,191,212.

Specification of Letters Patent. Patented July 18, 1916.

Application filed September 13, 1915. Serial No. 50,817.

To all whom it may concern:

Be it known that I, STANLEY G. MILLER, a citizen of the United States, residing at St. Paul, in the county of Ramsey and 5 State of Minnesota, have invented a certain new and useful Improvement in Grass Carpets, of which the following is a specification.

This invention relates to woven carpets, 10 and has for its object to improve the fabric of such carpets and to provide structural means for producing tone effect.

The invention consists in the combination and arrangement of parts described in the 15 specification, shown in the accompanying drawings, and more particularly set forth in the appended claims.

In the drawing, Figure 1 is a plan view 20 of a piece of carpet embodying the present invention; Fig. 2 shows a small portion of the carpet considerably enlarged; and Fig. 25 3 shows a portion of one of the woof strands with the wrapping therefor.

In the manufacture of carpets, and particularly of grass carpets, it is a common 25 practice to form the fabric by a warp composed of one kind of material and a woof of a different material. In grass carpets it is usual to use strands of various grasses 30 for the woof. It has heretofore been customary to produce a general tone effect by dyeing the grass composing the woof strands, and to vary the design by the arrangement and coloring of the warp. In 35 the present invention a novel means is provided for producing the general tone effect in the carpet without the necessity of dyeing the grass which may be left in its natural color. The same means which is used 40 for producing the tone effect also materially improves the carpet texture.

Referring to the drawing, the numeral 1 designates the strands which compose the woof of a carpet. These strands are made 45 up of a bundle of fibers 2. In the preferred embodiment of this invention, the fibers 2 are of grass and are laid side by side without twisting, so that they are substantially parallel with one another throughout the 50 length of the woof strands. The fibers are held together in a cylindrical strand as shown in Fig. 3, by a wrapping 3 preferable of heavy cotton thread which is wound spirally around the strand throughout its entire length. I prefer to use a double wrap 55

ping, one of the threads 3 passing around the woof strand in one direction and the other passing around the strand in the opposite direction, as clearly shown in Fig. 3 of the drawing. This construction is much 60 more efficient in holding the fibers of the strand in position than a single wrapping would be, even though the turns of the single wrapping were made close together, for the reason that the two wrappings in 65 crossing one another tend to hold each other in place and prevent the separation of the fibers in the strand.

The numeral 4 designates the strands of the warp, these strands being interwoven 70 with the woof strands in the usual manner. The arrangement and color of the warp strands may be varied in any of the usual ways to produce the figure effects of the carpet. This is accomplished by various 75 weaves of the warp and woof as well as by the various colored threads used for the warp.

The woof is preferably composed of undyed grass and the wrappings 3 of the woof 80 are preferably all of the same color in a given piece of carpet. The wrapping threads 3 are usually considerably smaller in size than the strands of the warp and individual threads are comparatively inconspicuous. Because of their position, however, around the strands of the woof they may be used for producing any tone desired 85 simply by using different colors for these wrapping threads. When a carpet is 90 viewed from a short distance, as it is when lying upon a floor, the individual wrapping threads are practically lost sight of but the whole carpet is given a tone depending upon the color of these threads. If green 95 threads are used, a greenish tone will be produced, or if brown or blue or yellow threads are used, the tone of the carpet will vary accordingly. If very dark threads, such as black, are used, a peculiar mottled 100 effect is secured, due to the criss-crossing of the wrapping threads which becomes more marked with dark threads than with lighter colors, since the natural color of the grass composing the woof is comparatively light. 105 In this way by the use of wrapping threads about the woof strands, I am enabled to produce a very strong fabric and at the same time secure different tone effects without the necessity of dyeing the grass from 110

which the carpet is made. It is of course apparent that the strands of the woof may be twisted, if desired, to any extent found advantageous.

5 Having thus described my invention, what I claim as new and desire to secure by Letters Patent of the United States is:—

10 1. In a grass carpet, the combination with a fabric having woof strands and warp strands, the woof strands being composed of fibers of undyed grass, of means for imparting a tone effect to said fabric comprising a spiral wrapping for said woof strands of a color different from said warp strands.

15 2. In combination with a fabric comprising warp strands and woof strands, the woof strands being composed of fibers of undyed grass, of means for holding said fibers together and for imparting a tone effect to said fabric consisting of threads wound spirally about said fibers in opposite directions and colored a different color from that of the warp strands of said fabric.

20 3. In combination with a fabric comprising woof strands and warp strands, the woof strands consisting of undyed grass fibers, of means for holding said fibers together in substantially cylindrical formation and for imparting a tone effect to said fabric, said means comprising wrappings consisting of threads wound spirally about said woof strands in opposite directions, and of a smaller diameter than said warp strands and colored a different color from said 30 warp strands whereby a tone effect is im-

parted to said fabric depending upon the color and winding of said wrapping threads.

4. In a grass carpet in combination with a fabric comprising woof strands and warp 40 strands, the woof strands being composed of undyed grass fibers, of color threads for imparting a tone effect to said fabric, said threads being wound spirally about said woof strands in opposite directions to form 45 a double wrapping therefor, and being of a contrasting color to the color of said fibers and differing in color from the warp strands.

5. The herein described method of imparting tone effect to grass carpet, having woof strands of undyed grass fibers arranged side by side, and warp strands interwoven with said woof strands, which consists of providing a spiral wrapping for 55 said woof strands of a color different from the color of both said woof strand fibers and said warp strands, said wrapping being wound about said woof strands in opposite directions and arranged to hold said strands 60 in substantially cylindrical formation.

In testimony whereof I have signed my name to this specification, in the presence of two subscribing witnesses, on this 10th day of September A. D. 1915.

STANLEY G. MILLER.
